United States Patent Office.

VIVIAN K. SPEAR, OF LYNN, MASSACHUSETTS.

Letters Patent No. 76,543, dated April 7, 1868.

IMPROVED MACHINE FOR POLISHING THE HEELS OF BOOTS AND SHOES.

The Schedule referred to in these Letters Patent and making part of the same.

TO ALL WHOM IT MAY CONCERN:

Be it known that I, VIVIAN K. SPEAR, of Lynn, in the county of Essex, and State of Massachusetts, have invented a new and useful Improvement in Machines for Polishing the Heels of Boots and Shoes; and I do hereby declare that the following is a full, clear, and exact description thereof, reference being had to the accompanying drawings, and the letters of reference marked thereon.

My invention consists in certain new and useful improvements upon a machine for which Letters Patent were issued to me, bearing date the 10th day of December, 1867.

In the accompanying drawings—

Figure 1 is a top view of my improved machine,

Figure 2 is a side elevation of the same, and

Figures 3 and 4 are detached views of parts hereinafter described.

A is the platform, on which the machine is mounted, and A' the frame, which supports the operative machinery.

C is the main driving-shaft, which is rapidly rotated by a strap passing round the pulley C', or by any other suitable means.

D is another pulley, mounted on the same driving-shaft, and which, by means of a cord or strap, c, passing round a pulley, a, on a shaft, E, rotates said shaft, with the brush-wheel E', waxing-wheel e, and shoulder-wheel e', mounted thereon.

F is a bracket or rest, in which the boot or shoe is suspended while the heel is being polished. This bracket is mounted on a sliding base-plate, F', in the platform A, which slides, longitudinally, between two guides, a¹ and a². The bracket F is mounted on a single post, B, rising vertically from the sliding plate F', having a swivel-joint at b, which allows the boot-holding bracket to be turned horizontally, so as to present the heel to the polisher at varying angles.

G is a lever, having its fulcrum, g, under the platform A, and H is a connecting-rod, hinged at one end to the said lever G, and at the other to the sliding plate F'.

I is a pawl, pivoted, at i, to the lever G, and engaging with a ratchet, i', made fast to the platform A, and j is a connecting-rod, pivoted at its lower end to said pawl I, and at its upper end to one branch of a forked lever, L, the other branch of which is pivoted to the lever G. A spring, l, operating to press the two levers L and G asunder, keeps the pawl I down on the ratchet.

When it is desired to move the boot-holding bracket forward or backward, the operator presses the upper ends of the levers L and G towards each other, which raises the pawl so that it will clear the ratchet, when, by means of the lever G, the sliding plate F' is easily moved in either direction, carrying the boot or shoe to or from the polisher. As soon as the pressure on lever L is released, the spring l causes the pawl instantly to engage with the ratchet, and hold the sliding plate F' firmly in place.

K is a horizontal shaft, passing through a sleeve, K', on the outer arm of the bracket F. On that part of the shaft K which is embraced within the sleeve K' there is a male-screw thread, and a match-thread in the sleeve, so that by turning the wheel m, on the outer end of the shaft K, a longitudinal movement is given to said shaft. The said shaft K has a detachable point, p, attached to it by a swivel-joint at p', which is to be used when the boot or shoe to be operated upon has a last in it; but when there is no last in the boot or shoe, said point p is detached, and a button, q, (fig. 3,) substituted.

R is a clutch, pivoted to the inner arm of the bracket F, and having a point, r, opposite and on a line with the pivot on which it turns, and a flange, r', to fit the front straight edge of the boot-heel. The boot or shoe is inserted between the points p and r, so that the point r will puncture the central part of the bottom of the heel, and the point p will puncture the top of the last, opposite the point r. The shaft K is then screwed forward until said points sufficiently penetrate the boot-heel and the last, to hold the boot or shoe suspended between said points; or, when there is no last in the boot or shoe, and the button q is substituted for the point p, the shaft K is screwed forward until said button presses on the inner sole, opposite the point r.

N is the heel-polisher, having an elastic bearing in a crank, n, as described in my said patent of December

10, 1867. This crank is oscillated by means of an eccentric, O, on the end of the driving-shaft C, and a connecting-rod, o', attached thereto by means of a cam-yoke, y, so that it gives the polisher a reciprocating motion in the line of an arc of a circle, as described in my said former patent. As this motion of the polisher is very rapid, I have found that, in a machine constructed as described in my said former patent, a disagreeable jarring accompanies the motion of the crank. In this invention, I obviate said defect by means of two elastic washers or bumpers, s and s', in the joint by which the connecting-rod o' is attached to the cam-yoke. The stem of the cam-yoke has an open slot, t, in it, and the connecting-rod passes through a socket in the outer end of said stem, and protrudes into said slot t. The elastic washers which I use are rubber rings, but any other suitable elastic substance may be used. The washer s is interposed between a shoulder on the connecting-rod and the outer end of the cam-yoke stem, and the washer s' is placed on the end of the connecting-rod which protrudes into the slot t, and is secured there by a screw-nut, t'.

The boot or shoe being suspended in the bracket or rest F, as before described, and the machine set in motion, said bracket may be turned on its swivel-jointed support, and the boot or shoe turned vertically in its bearings, so as to bring all parts of the heel to be polished successively in contact with the reciprocating polisher, as described in my said former patent.

The shoulder-wheel e' performs the function heretofore performed by an instrument known as a "shoulder-stick." The boot-heel is held against said wheel by hand, and turned so as to bring all parts to be operated upon by it successively in contact with the wheel.

I claim as my invention, and as improvements upon my said former invention, and desire to secure by Letters Patent—

1. In combination with the boot-holding bracket, mounted on a sliding base-plate, the lever G, with ratchet, pawl, and connecting-rod I, substantially as and for the purpose described.
2. In combination with the sliding bracket, lever G, connecting-rod I, and ratchet and pawl, I claim the forked lever L, spring l, and connecting-rod j, substantially as and for the purpose set forth.
3. In combination with the boot-holding bracket and polisher, as described, I claim the clutch R, with the central point r and flange r', substantially as and for the purpose specified.
4. In combination with the bracket and polisher, I claim the attachable and detachable button q, as and for the purpose described.

VIVIAN K. SPEAR.
